HANDLING OF ANNULAR ARTICLES

Ernest R. Comtois, Worcester, and Alfred F. Prentice, West Boylston, Mass., assignors to Morgan Construction Company, Worcester, Mass., a corporation of Massachusetts

Application May 9, 1955, Serial No. 507,020

10 Claims. (Cl. 198—177)

This invention relates to the handling of annular articles and, more particularly, to apparatus for transferring annular articles from a chain conveyor to a hook carrier.

In the handling of annular articles, there are many instances when it is desirable to transfer the articles one by one from a conveyor on which the annular article lies with its major axis vertical to a hook carrier in which the annular article is suspended with its major axis horizontal. Such a situation arises, for example, in the manufacture of metallic rod in which the rod is formed into a horizontal annular coil by a reel and after the coil is completed, the coil is ejected from the reel onto a horizontal chain conveyor which carries it away. The coils of rod are stored and handled, however, in a vertical position, and for this purpose, it is usual practice to transfer the horizontal coil to a hook carrier on which it hangs downwardly in a vertical position. A hook carrier carries the coil to a remote station where it is combined with a large number of similar coils for handling and storage. The apparatus of the type used heretofore is shown in the patent to Morgan No. 1,895,046 which was issued on January 24, 1933. However, the apparatus of the prior art has had a number of disabilities which are becoming more apparent. As time goes on, the coils are becoming bigger and bigger and, in many cases, the height of the coil is approaching a size which is comparable with the inside diameter thereof. This means that extreme care must be used in handling, lest the coil become disarranged; at the same time, it is very difficult to transfer such a "high" coil to a hook carrier in the conventional manner. Other problems have arisen as will be evident from the description which follows, but the disadvantages of the prior art have been obviated by the present invention in a novel manner.

It is, therefore, an outstanding object of this invention to provide a rugged and inexpensive apparatus for the handling of annular articles.

It is another object of this invention to provide an apparatus for the handling of annular articles which apparatus provides for the continuous support of the thickness of the coiling during the transfer from a horizontal to a vertical position.

It is another object of the present invention to provide an apparatus for transferring a coil of wire from a horizontal to a vertical position without disarrangement of the coils thereof.

It is a still further object of the present invention to provide an apparatus for the handling of metallic rod in coil form wherein the coil has a thickness dimension that is approximately equal to the inside diameter of the coil.

It is an object of this invention to provide an apparatus for transferring a metallic rod coil from a horizontal chain conveyor to a vertical hook carrier in such a manner that the last strand of rod to be coiled in the reel of a rod mill faces outwardly of the hook.

With these and other objects in view, as will be apparent to those skilled in the art, the invention resides

2

in the combination of parts set forth in the specification and covered by the claims appended hereto.

The character of the invention, however, may be best understood by reference to certain of its structural forms, as illustrated by the accompanying drawings in which:

Figure 1 is a plan view of an apparatus embodying the principles of the present invention,

Figure 2 is an elevation view of the apparatus,

Figure 3 is a sectional view with portions indicated by dotted lines of the apparatus taken along the line 33 of Figure 1, and

Figure 4 is a somewhat enlarged sectional view of the apparatus taken on the line 44 of Figure 1.

Referring first to Figure 1, wherein is best shown the general principles of the invention, a transfer apparatus, indicated generally by the reference numeral 10, is shown as comprising two main conveyors 11 and 12, a transfer conveyor 13, and a hook carrier 14. The main conveyors 11 and 12 are parallel to one another and extend at a right angle to the transfer conveyor 13. They are of the endless chain type and are provided with dogs 15 for moving the coil along the surface of the conveyor. The main conveyor chains 16 are best shown in Figure 4; they pass over an idler sprocket 17 at the end which is adjacent to the transfer conveyor 13. The transfer conveyor 13 is a double-track, endless-chain conveyor having upstanding dogs 18. A hook carrier consists of an endless chain 19 on which are hung a plurality of hooks 20. A chain 19 passes around idler wheels 21, 22 and 23, and a drive sprocket 24. The drive sprocket 24 and the idler wheel 23 are located so that the chain passes tangentially between the two along a line exactly overlying the center line of the transfer conveyor 13. The hooks dependent from the chain 19 lie in a central groove 25 in the surface of the conveyor 13 during the passage of the chain from the idler wheel 23 to the drive wheel 24. The drive sprocket 24 is mounted on a vertical shaft 26 which is geared to a horizontal shaft 27, driven through a gear reduction unit 28 by a motor 29. A transfer conveyor 13 is provided with two grooves in its surface which lie on either side of the central groove 25. These grooves 30 carry chains 31 bearing the dogs 18. The chains 31 are carried at one end and sprocket wheels 32 carried on a shaft 33 which is driven from the shaft 27 through a belt 34. At the other end, the chains 31 are carried on sprockets 35 mounted on a horizontal transfer shaft 36. As shown in Figures 1 and 4, the end of the conveyors 11 and 12 which lie adjacent the transfer conveyor 13 are provided with supplemental pusher chains 37 and 38 respectively, each lying centrally of the double-track of its respective main conveyor. Chain 37, for instance, is provided with a pusher dog 39 which rises above the surface of the main conveyor 11 on occasion. The chain 37 is mounted on a drive sprocket 40 at one end and an idler sprocket 41 at the other end.

The drive sprocket 40 is mounted on a shaft 42 which is connected through a belt 43 to a transfer shaft 44 on which the main conveyor drive sprocket 17 is mounted. The shaft 44 is connected through a gear unit 45 to the shaft 36, which, as has been described, is driven through the action of the chains 31 of the transfer conveyor 13.

The construction of the hooks 20 is best shown in Figure 2. Each hook consists of a shank 46, the upper end of which is pivoted at 47 to the chain 19. Extending from the lower end of the shank is a carrying bar 48. It is evident in the drawings a considerable portion of the shank 46 extends above the pivot 47 to form a counterbalance 49. The shank 46 and the carrying bar 48 extend at an angle of about 60° to one another. The balance and weight of the hook is such that when hanging freely from the pivot 47 the bar 48 is inclined slightly above horizontal and the shank 46 extends at a con-

siderable angle to the horizontal. Normally, the hooks 20 travel down the groove 25 in a freely hanging position. As they approach the left end of the transfer conveyor, however, a junction of the bar 48 and the shank 46 which is reinforced strikes a cam plate 50, so that the carrying bar is gradually tilted from a position slightly above horizontal to a position extending at a substantial angle to horizontal wherein the shank 46 is approximately vertical. As is evident in Figure 2, the cam plate 50 consists of a suitably supported curved metal plate located in the central groove 25 at the discharge end of the apparatus. The coils, indicated by the reference number 51, are shown in dotted lines as having a height which is approximately the same as the inside diameter thereof; they are thus susceptible to disarrangement and, of course, it is very difficult to cause the conventional hook to enter the center of the coil and to lift it. The dogs 18 are L-shaped and have one leg 52 considerably longer than the other leg 53. A pin 54 extends through the area of the dog 18 adjacent the junction of the legs 52 and 53, and serves to pivotally connect each dog to the chain 31. As the chain 31 moves along and the dog moves through the groove 30 the short leg 53 rests on the upper surface of an elongated cam track 55 which resides in the groove 30. As is evident in Figure 4, each cam track 55 consists of a curved metal channel suitably supported in its groove 30 by vertical side plates. In this position, the leg 52 extends vertically upwardly. The weight of the dog is balanced about the pin 54 in such a manner that the short leg 53 bears on the upper surface of the cam 55. The cam 55 is formed with a depression adjacent the discharge end of the transfer conveyor so that when the dog reaches the area of the cam 50 it begins to tilt so that the leg 52 takes up a position considerably inclined from the vertical; when the end of the cam 55 is reached, the dog takes a position wherein the elongated leg 52 is more or less horizontal. In Figure 4 is shown the manner in which the dog 18 rests on the cam track 55. Figure 4 also shows the details of the construction of the chain 31 and the manner in which it is carried on rollers 56.

The operation of the apparatus of the invention will now be clearly understood in view of the above description. The main conveyors 11 and 12 are operated continuously and each pair of dogs on these conveyors carries a coil 51. The gear ratios and drives which are described hereinbefore provide for the main conveyors 11 and 12 traveling at one-half the speed of the transfer conveyor 13, and, of course, the hook conveyor 19 travels at the same speed as the transfer conveyor 13. This means, then, that it is possible to provide every set of dogs 18 with a coil 51. Furthermore, every set of dogs 18 is matched with a corresponding hook 20 on the hook carrier 19. It is possible to keep the hook conveyor substantially full of coils, which is a very desirable situation. The dogs 15 on the main conveyors carry each coil to a position where it overlies the pusher apparatus 37 or 38. A dog 39 then rises and moves the coil 51 onto the transfer conveyor 13 where it is engaged by a pair of dogs 18. The transfer conveyor and hook carrier move together from right to left. The coil is moved along by its dog 18, the dog being maintained with the leg 52 in a vertical position by engagement of the short leg 53 with the cam track 55. Each coil 51 is preceded by a hook 20 which hangs freely, with its carrying bar raised slightly above horizontal. At first, there is no engagement between the hook 20 and the coil 51. When the hook 20 strikes the cam track 50, however, its carrier bar 48 has its outer end moved upwardly and because of the positional relationship between each corresponding dog 18 and hook 20 the end of the bar begins to extend upwardly into the center of the coil 51. Eventually, the lower edge of the coil nests into the juncture between the carrier bar 48 and the shank 46 of the hook and, because of the rapid rise

of the cam track 50 and a change in elevation of the chain 19 of the hook carrier, the forward side of the coil is lifted slightly. This means that the rearward side of the coil which is engaged by the dog 18 is inclined rearwardly. The cam track 55 takes care of this by permitting the elongated vertical leg 52 of the dog to assume a slightly inclined position to support the coil. Eventually, the hook is raised high enough so that it engages the coil completely, the straight carrier bar 48 serving to support the coil. When this situation is reached, it is no longer necessary to support the coil by means of the dog 18 nor is it necessary to push the coil along by means of that dog. At that time, the dog 18 drops off the end of the cam track 55 and assumes a position in which the elongated leg 52 is substantially horizontal and beneath the surface of the conveyor 13. The coil is then in a substantially vertical position entirely supported by the hook 20 and moves off with the hook carrier 19 for further processing. It is to be noted that the relationship between the cam track 50 and the changes in elevation of the chain 19 of the hook carrier is such that during its contact with the cam track 50 the hook is caused to change its aspect. The carrier bar 48 which in the freely-hanging position of the hook is slightly above horizontal slowly moves up toward a vertical position until it assumes the same angle to vertical as the elongated leg 52 of the dog 18. It is in this position that the coil begins to be supported by the hook carrier and the dog 18 is permitted to fall behind. It is to be noted that the coils 51 rest on the main conveyors with the strands in the same relationship as they were when they left the reel. This means that the uppermost strands are those which came out of the rod mill last and which were formed in the reel last. In the rolling of rod, particularly in a straight-through rod-finishing stand, it is impossible to avoid a considerable amount of "fin" at the rear end of the rod. This "fin" may appear on several turns of the coil and the finned section must be cut off, since it would not be acceptable to a person buying the rod. It is practically impossible to remove rod from the portion of the coil which is pressed against the shank 46. In the present invention, however, it is to be observed that the uppermost strands are those which are situated outwardly of the shank 46 and, therefore, are accessible for the removal of the finned end. The back end has to be trimmed as that is where the greatest fin end occurs.

It is obvious that minor changes may be made in the form and construction of the invention without departing from the material spirit thereof. It is not, however, desired to confine the invention to the exact form herein shown and described, but it is desired to include all such as properly come within the scope claimed.

The invention having been thus described, what is claimed as new and desired to secure by Letters Patent is:

1. Apparatus for the handling of annular articles comprising a horizontal transfer conveyor, a hook carrier having a portion which overlies the conveyor, the carrier arranged to move at the same speed as the conveyor, hooks depending from the carrier and residing in a groove in the conveyor during their passage thereover, dogs extending upwardly from the conveyor, and a cam track engaged by each dog to determine its aspect, the dogs engaging the articles and moving them in the direction of movement of the conveyor and the carrier, a hook associated with each dog and having the open end extending away from the direction of the movement, a second cam track engaged by each hook at the end of its travel with the conveyor, the second cam track tilting the free end of the hook upwardly so that it enters the center of the article.

2. Apparatus for the handling of annular articles comprising a horizontal transfer conveyor, a hook carrier having a portion which overlies the conveyor, the carrier arranged to move at approximately the same speed as the

conveyor, hooks depending from the carrier and residing in a groove in the conveyor, spaced dogs extending upwardly from the conveyor, means engaged by each dog to determine its aspect during its travel along with conveyor, each dog engaging an article and moving it in the direction of movement of the conveyor, a hook associated with each dog and having a free end extending away from the direction of movement, and means engaged by each hook during a portion of its travel with the conveyor, the said last-named means tilting the free end of the hook upwardly so that it enters the center of the article.

3. Apparatus for the handling of annular articles comprising a horizontal transfer conveyor, a hook carrier having a portion which overlies the conveyor, the carrier arranged to move at approximately the same speed as the conveyor, hooks depending from the carrier, spaced dogs extending upwardly from the upper surface of the conveyor, means engaged by each dog to determine its aspect during its travel along with conveyor, each dog engaging an article and moving it in the direction of movement of the conveyor, a hook associated with each dog during its travel above the upper surface of the conveyor and having its free end extending rearwardly of the direction of motion, and means engaged by each hook during a portion of its travel with the conveyor, the last-named means tilting the hook so that its free end enters the center of the article.

4. Apparatus for the handling of annular articles comprising a conveyor having a horizontal upper surface adapted to receive the articles, a carrier having a portion which overlies the conveyor, the carrier arranged to move at approximately the same speed as the conveyor, hooks depending from the carrier and residing in a centrally-located groove in the conveyor, spaced pairs of dogs extending upwardly from the upper surface of the conveyor and moving therewith, means engaged by each dog to determine its aspect during its travel along with conveyor and while extending upwardly from the upper surface thereof, each pair of dogs engaging an article and moving it in the direction of movement of the conveyor, one of said hooks associated with each pair of dogs during their travel above the upper surface of the conveyor and having its free end extending rearwardly of the direction of motion, and means engaged by each hook during a portion of its travel above the conveyor, the said last-named means serving to tilt the hook so that it enters the center of the annular article.

5. Apparatus for the handling of annular articles comprising a conveyor having a horizontal upper surface adapted to receive the articles one at a time, a carrier having a portion which overlies the center of the conveyor, the carrier arranged to move at approximately the same speed as the conveyor, hooks depending from the carrier and having a free-ended carrier bar at their lower ends, each carrier bar residing in a centrally-located groove in the upper surface of the conveyor during the passage of its hook over the conveyor, spaced pairs of dogs extending upwardly from the upper surface of the conveyor and moving therewith, means engaged by each dog to determine its aspect during its travel along with conveyor and while extending upwardly from the upper surface thereof, each pair of dogs engaging an article and moving it in the direction of movement of the conveyor, one of said hooks associated with each pair of dogs during their travel above the upper surface of the conveyor with the carrier bar extending rearwardly of the direction of motion, and means engaged by each hook during a portion of its travel with the conveyor, the last-named means serving to tilt the hook so that it enters the center of the annular article.

6. Apparatus for the handling of annular articles comprising an elongated conveyor having a horizontal upper surface adapted to receive the articles one at a time, a

conveyor having a portion which overlies the longitudinal center line of the conveyor, the carrier arranged to move at approximately the same speed as the conveyor, hooks depending from the carrier and having a free-ended carrier bar at their lower ends, each carrier bar residing in a centrally-located groove in the upper surface of the conveyor during the passage of its hook over the conveyor, spaced pairs of dogs extending upwardly from the upper surface of the conveyor and moving therewith, cam means engaged by each dog to determine its aspect during its travel with the conveyor and while extending upwardly from the upper surface thereof, each pair of dogs engaging an article and moving it in the direction of movement of the conveyor, one of said hooks associated with each pair of dogs during its travel above the upper surface of the conveyor and having its carrier bar extending rearwardly of the direction of motion and a second cam means engaged by each hook during a portion of its travel with the conveyor to tilt the hook so that it enters the center of the annular article as the hook and article travel together along the center line of the conveyor.

7. Apparatus for the handling of annular articles comprising an elongated conveyor having a horizontal upper surface adapted to receive the articles one at a time, a carrier having a portion which overlies the longitudinal center line of the conveyor and having hooks dependent therefrom, the carrier arranged to move at approximately the same speed as the conveyor, each hook having a free-ended carrier bar at its lower end, the bar extending away from the direction of movement of the carrier, each carrier bar residing in a centrally-located groove in the upper surface of the conveyor during the passage of its hook over the conveyor, spaced pairs of dogs extending upwardly from the upper surface of the conveyor and moving therewith, cam means engaged by each dog to determine its aspect during its travel along the conveyor and while extending upwardly from the upper surface thereof, each pair of dogs engaging an article and moving it in the direction of movement of the conveyor, one of said hooks associated with each pair of dogs during its travel across and above the upper surface of the conveyor, and a second cam means engaged by each hook during a portion of its travel with the conveyor to tilt the hook so that the free end of the carrier bar enters the center of the annular article as the hook and article travel together along the center line of the conveyor.

8. Apparatus for the handling of annular articles comprising an elongated conveyor having a fixed horizontal upper surface and a double movable chain adapted to receive the articles one at a time, a carrier having a portion which overlies the longitudinal center line of the conveyor between the chains and having hooks dependent therefrom, the carrier arranged to move at approximately the same speed as the conveyor, each hook having a free-ended carrier bar at its lower end, the bar extending away from the direction of movement of the carrier, each carrier bar residing in a groove located on the center line of the upper surface of the conveyor between the chains during the passage of its hook over the conveyor, spaced pair of dogs attached to the chains extending upwardly from the upper surface of the conveyor and moving therewith, a cam track beneath the upper surface of the conveyor engaged by each dog to determine its aspect during its travel along the conveyor and while extending upwardly from the upper surface thereof, each pair of dogs engaging an article and moving it in the direction of movement of the conveyor, one of said hooks associated with each pair of dogs during its travel across and above the upper surface of the conveyor, and a second cam track located in the groove in the conveyor engaged by each hook during a portion of its travel with the conveyor to tilt the hook so that the

free end of the carrier bar enters the center of the annular article as the hook and article travel together along the center line of the conveyor.

9. Apparatus for the handling of annular articles comprising a horizontal transfer conveyor, a carrier having hooks dependent therefrom, each having a portion which overlies the conveyor and removes articles singly from the conveyor, spaced dogs extending upwardly from the conveyor, each dog engaging an article and moving it in the direction of movement of the conveyor one of the said hooks associated with each dog and having a free end extending rearwardly of the direction of motion, and means engaged by each dog during a portion of its travel with the conveyor, the last-named means gradually tilting the dog rearwardly so that it supports the rearward portion of the article as the hook begins to remove it from the conveyor.

10. Apparatus for the handling of annular articles comprising a horizontal transfer conveyor, a carrier having hooks dependent therefrom and having a portion which

15

overlies and passes over the conveyor, each hook having a free end that extends rearwardly of the direction of motion, spaced dogs extending upwardly from the conveyor, each dog engaging an article and moving it in the direction of the conveyor, one of the said hooks associated with each dog and having a free end adapted to enter the center of an article and remove it from the conveyor, and a cam track underlying and engaged by the lower part of each hook during a portion of its travel with the conveyor, a cam track serving to tilt the free end of the hook upwardly so that it enters the center of the article as the hook and article travel together along the conveyor.
